PORTABLE INDEX FILE

Amato M. Matthew Pirone, Mount Vernon, N. Y.

Application March 23, 1948, Serial No. 145,278

Term of patent 7 years

(Cl. D74—2)

To all whom it may concern:

Be it known that I, Amato M. Matthew Pirone, a citizen of the United States of America, residing in the city of Mount Vernon, county of Westchester, and State of New York, have invented a new, original, and ornamental Design for a Portable Index File, of which the following is a specification, reference being had to the accompanying drawing, forming part thereof:

Figure 1 is a view in perspective of a portable index file showing my new design.

Figure 2 is a rear elevational view of the device shown in Figure 1 with the cover closed.

Figure 3 is a right end elevational view as seen from the right of Figure 2.

The side not shown is substantially the same as the side shown.

I claim:

The ornamental design for a portable index file, as shown and described.

AMATO M. MATTHEW PIRONE.
